DESIGN FOR A BILLFOLD

Louis A. Mueller, Springfield, Ohio, assignor to
The Springfield Leather Products Company,
Springfield, Ohio, a corporation of Ohio

Application January 22, 1938, Serial No. 74,485

Term of patent 7 years

To all whom it may concern:

Be it known that I, Louis A. Mueller, a citizen of the United States, residing at Springfield, in the county of Clark and State of Ohio, have invented a new, original, and ornamental Design for a Billfold, of which the following is a specification, reference being had to the accompanying drawing, forming part thereof.

The figure is a perspective view of a billfold, showing my new design.

The design appears entirely on the side of the billfold shown in the drawing, the opposite side being plain.

I claim:

The ornamental design for a billfold, as shown and described.

LOUIS A. MUELLER.
